UNITED STATES PATENT OFFICE.

CHARLES FREDERICK LORENZ, OF EAST ORANGE, NEW JERSEY, ASSIGNEE TO WESTINGHOUSE LAMP COMPANY, A CORPORATION OF PENNSYLVANIA.

ARC INCANDESCENT LAMP.

Application filed March 26, 1923. Serial No. 627,544.

This invention relates to electric incandescent lamps and more particularly to lamps adapted for motion-picture projection or those having concentrated light sources.

An object of my invention is the provision of an electric incandescent lamp which utilizes, in its construction, the principle of black-body radiation.

10 A further object of my invention is the provision of an electric-discharge lamp having one of its electrodes composed of a plurality of cells.

15 A further object of my invention is the provision of an electric-discharge lamp in which the electrodes are so positioned within the lamp as to be partially heated by reflected heat and light, whereby the energy put into the lamp may be conserved.

20 A still further object of my invention is the provision of a projection lamp which employs, in its construction, the black-body principle and also conserves some of the energy put into the lamp by reflection of 25 the radiation upon the light source.

Other objects of the invention will be apparent as the description proceeds.

In motion-picture projection lamps of the type which are more commonly used, a concentrated light source is provided by employing a series of helical coils disposed in a common plane and disposing in the spaces between such coils and directly behind the same, another series of correspondingly formed coils. The arrangement of the filament in this manner gives a solid source of light.

It has been observed, in these lamps, that the interior of the coil appears to have a 40 greater brightness than its outside. This effect is due to the reflections of light within the coil, and is referred to in the literature as the black-body effect. It is the purpose of my invention to utilize this principle in 45 designing a lamp for projection purposes.

In order that the energy which is dissipated in the form of radiant energy may be conserved, I may employ, as illustrated in one embodiment of my lamp, a reflector which is combined with the bulb thereof. The light and heat striking this reflector is directed backwardly upon the electrodes and the heat is thus conserved.

Referring now to the drawings, which

illustrate several embodiments of my invention,

Fig. 1 is a front view of a lamp having the reflecting surface applied thereto and also illustrating the electrodes in perspective to more clearly show their construction;

Fig. 2 is a front view of the interior electrode illustrated in Fig. 1;

Figs. 3 and 4 are longitudinal cross sectional and front elevational views, respectively, of a modified form of black-body radiator or electrode;

Fig. 5 is still another modification in which the cells are formed by the employment of concentric cylinders;

Fig. 6 is a modification in which the cellular construction is obtained by bending a corrugated strip of metal into a coil;

Figs. 7, 8 and 9 show other arrangements of the electrode to secure "black-body" effects.

Fig. 10 illustrates a form and arrangement of electrodes embodying the black-radiator principle but in which each electrode supports a portion of the lamellar elements which combine to form the cellular structure; and,

Fig. 11 is a transverse sectional view of the lamp taken on line XI—XI of Fig. 10.

In the lamp illustrated in Fig. 1, 12 indicates an envelope of spherical shape having an inner coating 13 of a reflecting material, such as silver or the like. A portion of this coating material is omitted from a section 14 of the bulb in order that the light which is generated within the envelope may be capable of emission therefrom.

The bulb or envelope 12 may be sealed to prevent any gas or air from passing into the same. The interior of the bulb is filled with a gaseous or inert environment which may be at such a pressure that an electrical discharge may be sustained between the electrodes, subsequently to be described. Ordinarily, a pressure of 600 millimeters of mercury is sufficient. I prefer to employ, as the gaseous medium, a gas which is inert with respect to the electrode material. A suitable gas is argon, nitrogen, neon, helium, and the like, or mixtures thereof.

The light is secured by heating a pair of electrodes 15 and 16 to incandescence; this being accomplished by passage of an elec-

trical discharge between the same. The current for this discharge may be conducted to the electrodes by the leading-in wires 18 and 19, which latter may also furnish support for the electrodes. If desired, the electrodes 15 and 16 may be supported by auxiliary means (not shown).

In order that the arc may be passed between the electrodes 15 and 16, they are spaced apart an appropriate distance, such distance depending upon the particular gas pressure employed, character and purity of the gas, electrode material, etc. With a gas pressure of 600 millimeters of mercury, the distance should preferably be about 3 millimeters.

The electrode 15, in the embodiment illustrated in Fig. 1, comprises a narrow band of a conductive material, such as tungsten or the like. This band is bent in the form of a circle, open at its lower portion 17, and may be retained in this position by any desired means or may be given this shape initially. Within the space enclosed by the electrode 15, is positioned the electrode 16, the latter being of a special construction, about to be described, in order to obtain the black-body effect.

In the embodiment illustrated in Fig. 1, the electrode 16 is composed of a plurality of cells or honeycombed structure 20 which are formed by the assembly of a number of small tubes 21 composed of a refractory metal, such as tungsten or the like. These tubes may be held in position in any desirable manner, for example, by shrinking a band 21' thereabout. It is preferred that they be arranged in accordance with some symmetrical design. In Fig. 2, this design consists of an outer circle of these tubes, an inner circle of tubes and a single tube positioned at the center of these circles.

This construction provides a series of concentric cells. If desired, these cells may be closed at their rear ends in order to secure a better reflection of the light therein.

To minimize the proportion of the radiation from the sides with respect to the total radiation and, at the same time, to retain the black-body effect, I find it preferable to construct the cells so that their depths are great in comparison with their individual widths, and also to have the depth of the cells shallow in comparison with the total width of the group of cells constituting the electrode.

In Figs. 3, 4, 7, 8 and 9, the cellular or honeycomb structure is formed by dividing the tubular member 21' into a number of smaller openings or cavities 20 by partitions or lamellar elements 22. Referring particularly to Figs. 3 and 4, the partitions 22 are arranged radially within the cylinder 21' and may be secured in their adjusted positions by casting a block 24 of refractory metal about their lower edges. Other

methods may be employed for securing the partitions in their adjusted positions. With this construction, one end of the cells will be closed, thus increasing the black-body effect. In Figs. 7 and 8, the tubular member 21' is given a square configuration, and the space enclosed thereby is divided into a plurality of cells 20 by arranging the partitions parallel to the walls of the tubular member 21'. The partitions in Fig. 7 cross each other at right angles and may be secured in their adjusted positions by providing a slotted arrangement similarly to that provided in the partitions used in egg crates. In Fig. 8, the arrangement of the partitions is somewhat similar to that illustrated in Fig. 7 except for the omission of the cross partitions. In Fig. 9, the partitions 22 are given a saw-tooth formation and may be separated by suitable plates 23'.

Another arrangement of cells may be secured by the construction illustrated in Fig. 5 wherein the cells 20 are formed by disposing a plurality of cylinders 21', one within another but spaced apart. This construction provides a series of circular cells or openings 20. In Fig. 6, the cellular structure is formed by bending a corrugated band 23 upon itself in the form of a coil. The corrugations provide cells 20. The wound strip is retained in its position by an outer tube or cylinder 21'.

A further modification of my invention is illustrated in Fig. 10 in which the cellular structure for producing the black-body effect is obtained by making each electrode a counter part of the other. In the embodiment illustrated, each of the electrodes is formed of a strip of tungsten metal 25 having projecting, at right angles from one side thereof, a plurality of flat strips 26 of the same width as the body material 25. The strips 26, in assembling the electrodes within the lamp, are inserted in the spaces between strips 26 of the opposed electrode. In this manner, the space between the strips 26 of the one electrode is divided into two cells by a single strip 26 of an opposed electrode. This construction enables the electrodes to be assembled with greater facility and simplifies considerably their construction.

A lamp of this type may find considerable usage as a projection lamp and, to this end, the electrodes are illustrated as being disposed in a lamp having a tubular envelope 120 27. Electrodes 25 are connected, by leading-in wires 28 and 29, to base 30 and center contact 31, whereby current may be supplied to the electrodes and an electrical discharge caused to take place therebetween.

Various modifications will suggest themselves to those skilled in the art, but I contemplate all such modifications as come within the spirit of my invention as defined by the scope of the appended claims.

What is claimed is:

1. An electric lamp comprising an envelope having an inert atmosphere therein, a concentrated light source, said light source comprising a pair of concentrically disposed electrodes within said envelope, the inner electrode comprising a plurality of lamellar elements adapted to produce black body radiation.
  - 10 2. An electric lamp comprising an envelope having an inert atmosphere therein, a concentrated light source comprising a pair of electrodes within said envelope, one of said electrodes comprising an enclosing band of conducting metal, the other of said electrodes being disposed within the space enclosed by the first electrode and comprising a plurality of lamellar elements so disposed with respect to each other as to form a plurality of wells or pockets.
  - 15 3. An electric lamp comprising an envelope having an inert atmosphere therein, a concentrated light source comprising a pair of electrodes within said envelope, one of said electrodes comprising a band of conducting metal bent to arcuate shape, the other of said electrodes being disposed with-
- in the space enclosed by the first electrode and comprising a plurality of lamellar elements so disposed with respect to each other as to form a plurality of wells or pockets, said pockets being of greater individual depth than width but of less depth than the width of the lamellar electrode.
- 20 4. An electric lamp comprising an envelope having an inert atmosphere therein, a concentrated light source comprising a pair of electrodes within said envelope, one of said electrodes comprising a ring shaped band of conducting metal, the other of said electrodes being disposed within the space enclosed by the first electrode and comprising a plurality of lamellar elements so disposed with respect to each other as to form a plurality of wells or pockets, said pockets being of greater depth than width and having their longitudinal axes substantially parallel to the direction in which the light is projected.
- 25 In testimony whereof, I have hereunto subscribed my name this 24th day of March, 1923.

CHARLES FREDERICK LORENZ.
